UNITED STATES PATENT OFFICE

2,055,733

REFRIGERATION STRUCTURE

Russell T. Smith, Greenville, Mich., assignor to
 Gibson Electric Refrigerator Corp., a corpora-
 tion of Michigan

Application March 26, 1934, Serial No. 717,516

12 Claims. (Cl. 62—118)

This invention relates to improvements in refrigeration structure and, more particularly, to refrigeration apparatus of the cyclic absorption type.

5 An object is to provide an assembly, the components of which are disposed to provide a maximum of efficiency in operation and at the same time are conveniently arranged. A further object is to provide an assembly that is simple and 10 inexpensive to construct and durable and reliable in operation.

In general, the system comprises a generator-absorber, a condenser, an evaporator, a freezing unit, and a generator heating unit. One feature of the improved construction is the provision 15 of a generator in the rear of the cabinet, a heating unit below the generator and the cabinet, and means to readily withdraw and replace the heating unit in its proper position below the generator. A further feature is the disposition 20 of the condenser tank within the cabinet walls, the cabinet walls preferably comprising solid sheet panels extending from the base of the cabinet to the top of the condenser tank.

25 The general principles of operation of the type of refrigeration to which this invention relates are well known and a brief description of the basic principles will suffice. The system is substantially a closed one and in operation the generators are preferably filled with a solution of aqua ammonia. When the heaters are burning, the ammonia rises in vapor form to the water-cooled condenser where the vapor is cooled, condensed and flows in liquid state to the evaporators below. In the second stage of the cycle, the 30 absorption period, the burners are off and when the generator cools with a resultant pressure drop, the water therein absorbs the ammonia vapor, reducing the pressure in the evaporator and permitting the liquid ammonia therein to 35 evaporate, thereby cooling the evaporator and eventually freezing the brine in the freezing unit below the evaporator. A further feature of the present invention is the provision of means for preventing a pumping action or "spilling over" 40 in the liquid overflow line during the cooling cycle.

45 Other features and advantages will appear in the course of the following description in conjunction with the accompanying drawings, in which—

50 Figure 1 is a view partly in front elevation and partly in section along lines 1—1 of Fig. 2; Fig. 2, a vertical sectional view along line 2—2 of Figs. 55 1 and 3; Fig. 3, a vertical sectional view along

line 3—3 of Fig. 2; Fig. 4, a horizontal sectional view along line 4—4 of Fig. 2; and Fig. 5, an enlarged sectional view of the evaporator and freezing unit taken along the line 5—5 of Fig. 1.

5 Referring to the drawings, the improved apparatus includes a cabinet, indicated generally at A; a removable heating unit B disposed beneath the cabinet; a generator-absorber device C above said heating unit; a water-cooled condenser D within said cabinet; an evaporator E disposed below the condenser D and connected thereto; and a freezing unit F below said evaporator.

The cabinet A is an insulated box 5 equipped with side walls 6 comprising single sheets of metal extending from the base of the box to the 15 top of the condenser tank, a detachable top 7, a door 8 and legs 9. To the rear of the cabinet and spaced therefrom a generator-housing chamber 10 is detachably secured to the cabinet, for example, the generator chamber may be secured 20 to the cabinet by bolts 10^a and wing nuts 10^b. The generator-absorber device preferably comprises a pair of cylindrical tanks 11 and 11^a horizontally disposed one above the other in the 25 lower part of the chamber 10. The contents of the generator may circulate freely therebetween by means of the conduits 11^b.

30 The generator heating unit B, disposed beneath the generator 11, is equipped with a carriage frame 12 slidably mounted on rails 13 suspended from the bottom of the cabinet. The unit comprises heaters 14 and a fuel supply 15. A handle 16 is secured to a forward portion of the unit and extends to the front of the cabinet where its forward end 16^a may be retained in the spring catch 35 17 at the bottom of the cabinet front. The length of the handle is such that when it is secured in its catch, the heaters 14 are properly disposed beneath the generator 11.

35 Returning to the generator-absorber structure, 40 it is to be noted that the tanks 11 and 11^a are preferably equipped with heat-conducting fins 18 and the wall of the generator chamber adjacent the cabinet with a shield 19. The shield houses and carries in its lower portion a generator trap 45 overflow pipe 20 discharging into a lower portion of the generator 11.

45 A vapor return conduit 21 leads upwardly from a lower portion of the generator 11 through the upper generator vessel through a trap 22 and 50 header 22^a, disposed one above the other, and forms a U-shaped bend 21^a at the top of the chamber 10. An inner vapor rectifier tube 23 surrounding the conduit 21 extends from the top of the upper generator tank 11^a into the gen- 55

therefrom, but the appended claims should be construed as broadly as permissible, in view of the prior art.

What I regard as new, and desire to secure by Letters Patent is:

1. Refrigeration apparatus of the type described comprising a generator-absorber device; a generator trap; generator heating means; a condenser; an evaporator; a cabinet housing said condenser and evaporator; a chamber removably secured to said cabinet housing said generator-absorber device and generator trap; a shield within said chamber and interposed between said cabinet and generator device; and a generator trap overflow carried by said shield.

2. Refrigeration apparatus of the type described comprising a generator; a condenser; an insulated compartment; an evaporator including a receiving tank within said compartment; a freezing unit having evaporator coils originating in said receiving tank; a vapor return conduit from said receiving tank to said generator; and a liquid supply line from said condenser emptying into said vapor return conduit substantially above the receiving tank and without said compartment.

3. In refrigeration structure of the type described, a generator absorber; a condenser; an evaporator including receiving means; freezing means having evaporator coils depending from said receiving means and terminating in a manifold; a vapor return conduit from said evaporator to said generator; an expansion tube opening into said vapor return conduit; a liquid by-pass; and an overflow line from said manifold to said expansion tube, said line leading through a cool section of said evaporator.

4. In refrigeration structure of the type described, a generator-absorber; a condenser; an evaporator including receiving tanks; freezing means including evaporator coils depending from said tanks and terminating in a sump; a vapor return conduit from the upper section of one of said receiver tanks to said generator presenting a U-shaped portion rising above said receiving tanks and generator; and a sump overflow and expansion line said overflow draining into said vapor conduit on the generator side of said U above the evaporator.

5. In refrigeration structure of the type described, a generator-absorber; a condenser; an evaporator including receiving tanks; freezing means including evaporator coils depending from said tanks and terminating in a sump; a vapor return conduit from the upper section of one of said receiver tanks to said generator presenting a U-shaped portion rising above said receiving tanks and generator; a sump overflow and expansion line passing through a cold portion of said evaporator means; and a liquid by-pass from said expansion line entering said vapor conduit approximately at a level with the top of said receiving tanks.

6. Refrigeration apparatus of the type described comprising a generator; a condenser; an insulated compartment; an evaporator within said compartment; a vapor return conduit from said evaporator to said generator; and a liquid supply line from said condenser emptying into said vapor return conduit above said evaporator without said compartment, whereby said liquid flows into said evaporator.

7. In refrigeration structure of the type described a generator; a condenser; an evaporator; an overflow line from the bottom of said evaporator to said generator, said overflow line rising

above the level of the top of the evaporator and having an expanded portion therein in the portion thereof rising from said evaporator; and a liquid by-pass outlet from said expanded portion.

8. In refrigeration structure of the type described, a generator; a condenser; an evaporator; a vapor return line from said evaporator to said generator; an overflow tube from the bottom of said evaporator to a point in the vapor return line above said evaporator, said overflow tube having an expanded portion therein whereby vapor entrained with liquid separates from said liquid; and a liquid by-pass from said expanded portion below the top thereof, whereby said expanded portion is prevented from completely filling with liquid.

9. In refrigeration structure of the type described, a generator; a condenser; an insulated compartment; an evaporator within said compartment; a connection from said generator to said condenser, said connection having therein a trap opposing a column of liquid to vapor which would otherwise return from said condenser to said generator; a vapor return conduit from the top of said evaporator to said generator, said vapor return conduit rising above the top of said evaporator; and a pipe from the bottom of said condenser emptying into said vapor return conduit without said compartment at a point above said evaporator and adjacent thereto.

10. In refrigeration structure of the type described, a generator; a condenser; an insulated compartment; an evaporator in said compartment; a vapor return conduit from the top of said evaporator to said generator, said conduit presenting an inverted U-shaped portion rising above said evaporator; and a connection from said condenser to the side of said U-shaped portion connected to said evaporator, said connection being without said compartment.

11. In refrigeration structure of the type described, a generator; a condenser; an evaporator; a vapor return conduit from the top of said evaporator to said generator presenting an inverted U-shaped portion rising above said evaporator; a liquid overflow from the bottom of said evaporator to said vapor return conduit at a point slightly above said evaporator, said overflow having an expanded portion therein; and a vapor venting conduit from the top of said expanded portion to a point in said vapor return conduit above said overflow.

12. In refrigeration structure of the type described, a cabinet; a generator of substantially cylindrical shape, said generator being mounted at the back of said cabinet; a condenser; an evaporator; operative connections between said generator, condenser, and evaporator; a generator heating unit; supporting means therefor, said means being so constructed and arranged that said heating unit may be withdrawn to the front of said cabinet and returned to its operative position beneath said generator in a direction substantially perpendicular to the axis of said generator; a handle member attached to said supporting means and extending therefrom to the front of said cabinet when said heating unit is in its operative position; and latch means at the front of said cabinet adapted to engage said handle when said heating unit has been returned to its operative position, whereby said heating unit is properly disposed beneath said generator.

晴
寒流過後，天氣晴朗，風和日暖，氣溫也較高，約在15度左右。中午時分，我到城外的農田裡去採集，發現了不少昆蟲，有蝶、蛾、甲蟲、昆蟲等。在農田裡，我還發現了一隻小鳥，它在農田裡飛來飛去，似乎在尋找食物。我仔細觀察，發現這是一隻小麻雀，它有著鮮紅的喙，黑色的羽毛，非常可愛。我將它捉住，並將它放回農田裡，讓它能夠自由地飛翔。
